(21) Appl. No.: **29/177,596**

CLAIM

(22) Filed: **Mar. 10, 2003**

The ornamental design of an electronics components package element, as shown and described herein.

(51) **LOC (7) Cl.** **13-03**

DESCRIPTION

(52) **U.S. Cl.** **D13/182**

(58) **Field of Search** D13/182; 29/602.1;
174/17 VA; 200/306; 220/260; 335/78,
80, 122, 132, 151, 199, 202; 361/626, 633,
819; 439/362, 564, 709, 710, 715, 716

(56) **References Cited**

FIG. 1 is a side elevation view of a first embodiment of an electronics component package, showing our new design;
FIG. 2 is a top plan view thereof;
FIG. 3 is a bottom plan view thereof;
FIG. 4 is a front elevation view thereof;
FIG. 5 is a side elevation view of a second embodiment of an electronics component package, showing our new design;
FIG. 6 is a top plan view thereof;
FIG. 7 is a bottom plan view thereof; and,
FIG. 8 is a front plan view thereof.

UNITED STATES PATENT AND TRADEMARK OFFICE
CERTIFICATE OF CORRECTION

PATENT NO. : Des. 487,255 S
DATED : March 2, 2004
INVENTOR(S) : Dang et al.

Page 1 of 1

It is certified that error appears in the above-identified patent and that said Letters Patent is hereby corrected as shown below:

Title page, Item [54] and Column 1, line 1,
Title, “**ELECTRONICS COMPONENT PACKAGE ELEMENT**” should read
-- **ELECTRONICS COMPONENT PACKAGE** --

Title page,
DESCRIPTION, “**FIG. 8** is a front plan view thereof.” should read -- **FIG. 8** is a front elevation view thereof. --

Signed and Sealed this

Twenty-ninth Day of June, 2004

JON W. DUDAS
Acting Director of the United States Patent and Trademark Office
